UNITED STATES PATENT OFFICE.

WILLIAM C. HENDERSON, OF PASO ROBLES, CALIFORNIA.

STARTING DEVICE.

1,214,917.

Specification of Letters Patent.

Patented Feb. 6, 1917.

Application filed March 10, 1916. Serial No. 84,974.

To all whom it may concern:

Be it known that I, WILLIAM C. HENDERSON, a citizen of the United States, residing in the city of Paso Robles, in the county of San Luis Obispo and State of California, have invented a new and useful Improvement in Starting Devices, of which the following is a specification.

My invention relates to starting devices for internal combustion motors and the like wherein a rotatable element operates in conjunction with pistons and a clutch on the crank shaft of the motor to be started; and the objects of my invention are—

15 First, to provide an improved starting device for internal combustion motors and the like.

Second, to provide an improved rotatable element normally disengaged from the crank shaft of the motor and improved means for rotating and connecting the said element with the crank shaft of the motor simultaneously.

Third, to provide improved means whereby the device may be returned to a normal or starting position after having started the motor.

I accomplish these several objects by means of the device disclosed in the drawings forming a part of the present specification, wherein like characters of reference are used to designate similar parts throughout the said specification and drawings, and in which—

35 Figure 1 is a broken plan view of the front portion of a motor vehicle disclosing the application of my improved device.

Fig. 2 is a side elevation of the device as disclosed in Fig. 1 but removed from the 40 vehicle.

Fig. 3 is an enlarged broken longitudinal sectional view disclosing the relative arrangement of the pistons when in a normal or starting position.

45 Figs. 4, 5 and 6 are horizontal sectional views of the controlling valve in a neutral, starting and return to normal positions, respectively.

Fig. 7 is a transverse sectional view taken 50 on line 7—7 of Fig. 1 of the drawings in the direction indicated by the arrow.

Fig. 8 is a sectional view on an enlarged scale taken on line 8—8 of Fig. 1 in the direction indicated.

55 Referring to the drawings, the numeral 1 is used to designate the crank shaft of an internal combustion motor having the usual

clutch portion 2 thereon for the reception of the starting or cranking handle, not shown.

60 A rotatable element is mounted in front of and normally disconnected from the end of the crank shaft 1 whereby said shaft 1 may be engaged and rotated and comprises a sleeve 3 slidably and rotatably mounted in alinement with the said shaft 1. The sleeve 3 is provided with a clutch portion 4 adapted to engage the clutch portion 2 of the shaft 1 and also a pulley 6 which is secured to the outer end thereof.

70 Upper and lower cylinders 7 and 8 are used as operating and returning cylinders respectively and are provided with suitable pistons 9 and 11. The cylinders are arranged preferably parallel with the motor 75 crank shaft 1 and are secured to the frame 12 by means of suitable blocks 14 which also act as cylinder ends.

Each cylinder 7 and 8 is provided with an extension 16 and 17 terminating in a third 80 block 19 having pulleys 21 rotatably mounted therein.

85 A suitable cable 22 is wound several turns around the pulley 6 and has the ends thereof secured to the piston-rods 23 and 24 of the pistons 9 and 11 respectively. A four way controlling valve casing 26 is provided with an exhaust port 27, a port 28 connected to a supply or source of compressed air, not shown, and ports 29 and 31 which lead to the cylinders 7 and 8 respectively through suitable pipes 49 and 51.

90 The valve 32 is provided with channels 33 and 34 arranged to connect various ports mentioned. The valve stem 36 is provided with a lever 38 to which is operatively connected a rod 39 which is pivotally connected to a lever 41 mounted upon the frame of the vehicle whose outer end engages a groove 42 in the sleeve 3, the purpose of which will 95 hereinafter be more fully described.

100 A rod 43 is also connected to the lever 38 of the valve stem 36 and to a short depending arm 44 of a rock shaft 46 rotatably mounted upon the frame of the vehicle and 105 provided with an operating lever 47.

The operation is as follows:

110 Normally the sleeve 3 and the clutch portion 4 thereof are held away from the end of the crank shaft 1.

By moving the lever 47 in the direction indicated by the arrow in Fig. 2 of the drawings, the valve 32 is moved to the position indicated in Fig. 5 of the drawings and si-

multaneously causes the rod 39 and lever 41 to move the sleeve 3 toward the crank shaft 1 and cause the clutch portion 4 to engage the clutch portion 2 of the said crank shaft 1. 5 The compressed air will enter the port 28, channel 33, port 29 and cylinder 7 in front of the piston 9 and move the said piston toward the opposite end of the cylinder 7. This will cause the cable 22 to rotate the 10 pulley 6 and the crank shaft 1.

Referring to Fig. 5 of the drawings, it will be observed that the port 31 which connects with what I term return to normal cylinder 8 through the pipe 51, is connected 15 by means of the channel 34 to the exhaust port 27 so that the piston 11 is free to move within the cylinder 8 as the piston 9 moves in the cylinder 7 in the opposite direction.

In order to return the starting device to a normal or starting position, the lever 47 is 20 moved in the opposite direction which will cause the clutch 4 of the sleeve 3 to be disengaged from the clutch 2 of the crank shaft 1 and simultaneously move the valve to the 25 position indicated in Fig. 6 of the drawings, where it will be observed that the operating cylinder 7 is connected to the exhaust port 27 by means of the channel 34 while the return to normal cylinder 8 is connected to 30 the source of compressed air port 28 through a channel 33 and the pipe 51.

The compressed air thus entering the return to normal cylinder 8 will move the piston 11 back to a position indicated in Fig. 35 3 of the drawings and through the medium of the cable 22 also move the piston 9 in the operating cylinder 7 to a normal position as disclosed in the said figure.

The rod is provided with a suitable take 40 up mechanism consisting of the usual collars 52 and the springs 53 arranged on either side of a pin 54 set within the end of the lever 38 of the valve stem 36 in order to insure engagement of the clutch portions 2 45 and 4 when the valve and other parts of the starting device are in operating position, and also to allow the sleeve 3 to be pushed away from the rotating crank shaft 1, should the said crank shaft pick up suddenly, without jarring the hand of the operator or jerking the lever 47 out of his hand.

It is obvious from the foregoing that I have provided an improved starting device for internal combustion motors and the like 55 wherein a rotatable element is caused to engage and spin the crank shaft of the motor.

Having thus described my invention what I claim as new and desire to secure by Letters Patent is—

60 1. A starting device for internal combustion motors comprising a sleeve rotatably and slidably mounted in alinement with and adapted to engage the crank shaft of the

motor and normally disconnected therefrom; a pulley secured to the sleeve; a pair 65 of cylinders; a pair of pistons slidably mounted within the cylinders; a cable wound around the pulley and having the ends thereof connected to the pistons; a source of compressed air; and means adapted 70 to simultaneously connect the sleeve with the crank shaft and the source of compressed air with one of the cylinders and thereby spin said crank shaft.

2. A starting device for internal combustion motors comprising a sleeve rotatably and slidably mounted in alinement with and adapted to engage the crank shaft of the motor and normally disconnected therefrom; a pulley secured to the sleeve; a pair 80 of cylinders; a pair of pistons slidably mounted within the cylinders; a cable wound around the pulley and having the ends thereof connected to the pistons; a source of compressed air; means adapted to 85 simultaneously connect the sleeve with the crank shaft and the source of compressed air with one of the cylinders and thereby spin said crank shaft; and to disconnect the 90 sleeve from the shaft and to connect the compressed air to the other cylinder and thereby return the starting device to a starting position.

3. A starting device for internal combustion motors comprising a sleeve rotatably 95 and slidably mounted in alinement with and adapted to engage the crank shaft of the motor and normally disconnected therefrom; a pulley secured to the sleeve; a pair of cylinders; a pair of pistons slidably mounted 100 within the cylinders; a suitable cable wound on the pulley, and having the ends thereof connected to the pistons; a source of compressed air; a valve arranged to connect either cylinder with the source of compressed 105 air and the other cylinder with the atmosphere; a lever operatively connected to the sleeve and adapted to connect and disconnect the same with the crank shaft; and means 110 operatively connected to the valve and to the lever and adapted to operate the same whereby one cylinder may be connected to the compressed air and the other to the atmosphere and the sleeve to the crank shaft 115 thereby rotating the sleeve and spinning the crank shaft, and to disconnect the sleeve from the crank shaft and to operate the valve whereby the first cylinder may be connected to the atmosphere and the second cylinder to the compressed air source thereby 120 returning the starting device to a normal or starting position.

In witness whereof I hereunto set my signature.

WILLIAM C. HENDERSON.
